By Attorney.

UNITED STATES PATENT OFFICE.

FREDERICK B. HIBBARD, OF PHILADELPHIA, PENNSYLVANIA.

VALVE.

1,275,920.

Specification of Letters Patent. Patented Aug. 13, 1918.

Application filed August 1, 1917. Serial No. 183,819.

To all whom it may concern:

Be it known that I, FREDERICK B. HIBBARD, a citizen of the United States, residing at Philadelphia, in the county of Philadelphia, State of Pennsylvania, have invented a new and useful Valve, of which the following is a specification.

My invention relates to improvements in valves, and is especially applicable to bibs or faucets, but may obviously be applied to other devices.

The object is to provide a valve simple in construction, easily operated, that shall be self-seating and self-grinding, that shall be fluid tight without requiring the usual washer.

Referring to the drawings, which illustrate merely by way of example a suitable embodiment of my invention—

20 Figure 1 is a longitudinal vertical section taken on the line 1, 1 of Fig. 4, showing the valve closed.

Fig. 2 is a similar view showing the valve open.

25 Fig. 3 is a vertical cross-section on line 3, 3 of Fig. 1.

Fig. 4 is a plan view with the cap or housing removed.

Fig. 5 is a side elevation of the valve.

30 Fig. 6 is a plan view of same.

Similar numerals refer to similar parts throughout the several views.

In the specific embodiment illustrated by way of example, the valve 7 is shown as circular in plan provided with a flat and perfectly smooth working side adapted to rest and to be moved forward and backward on the seat 8 of the body of the bib 19, by the lever 9 projecting into the recess 10 on the underside, thereof, to open and close the outlet port 11. The inlet port 12 in communication with the source of fluid supply is always open to the chamber 13 formed by the housing or cap 14 surmounting said body 19, so that the pressure of the fluid, either liquid or gas, within the housing 14

is always exerted on the top of the valve 7, when the same is in the closed position. This pressure serves to maintain said valve fluid tight.

The periphery of the valve member 7 is provided with diagonally arranged grooves 15, so that the fluid, issuing from the port 12 and impinging said grooved periphery as said fluid passes out of port 11, when the valve is in the open position, will cause said valve member 7 to rotate about the head or ball 16, seated in the recess or socket 10. It will be understood that when port 11 is open the pressure above and below the valve 60 member 7 will be more nearly equalized and said member will be free to rotate in response to the force of the fluid impinging upon the said grooved periphery. This turning of the valve member upon its seat, 65 with very light pressure, whenever port 11 is open, serves to cause an equal wear at all points of contact between the valve member and its seat, so that said valve member becomes self-grinding and self-adjusting, 70 with the result that a fluid tight joint is maintained indefinitely. The greater the pressure above the valve member 7 the tighter becomes the joint.

The coacting parts may be made of sufficient weight or thickness to permit of practically indefinite wear.

The lever 9 is shown as projecting through a suitable bushing 18 in the body 19 of the faucet or bib and its outer end 80 connected with the handle 20.

The special tapered or flaring inclined formation of the grooves is especially advantageous in coöperating with the stream of fluid passing said valve when the valve 85 is in the open position to cause a slight rotation thereof.

What I claim is—

1. A chambered body having a discharge port, a flat valve seat surrounding the port, 90 a sliding valve member, mechanical means for actuating the same to open and close the

discharge port, and means whereby the passage of fluid through the discharge causes a rotative movement of said valve member.

2. A chambered body having a port and 5 a flat valve seat surrounding the port, a sliding valve therefor and means whereby the fluid passing through the port causes a rotative movement of the valve.

3. A chambered body having a port and 10 a flat valve seat surrounding the port, a sliding valve therefor having peripheral grooves as means whereby the valve is given a rotative movement on its seat by the passage of the fluid.

15 4. A chambered body having an intake and a discharge port and a flat valve seat surrounding the discharge port, a flat valve slideable on said seat having peripheral grooves as means for automatically rotating 20 the valve member as it is moved to uncover the port.

5. A chambered body having a discharge port and a flat valve seat surrounding the port, a valve member slideable on the seat to 25 open and close the port, said valve member of such formation that when actuated to uncover the port it is given a rotative movement by the action of the fluid thereon.

6. A chambered body having a discharge 30 port and a flat valve seat surrounding said port, a flat valve member slideable on the seat to open and close the port, a hand lever for causing the sliding movement, and means for automatically causing a rotative 35 movement of the valve member when actuated by the hand lever.

7. A chambered body having a port and a flat valve seat, a flat valve member adapted to lie loosely by force of gravity and the 40 pressure of the fluid upon said seat, mechanical means for moving the valve member forward and backward upon its seat and means for automatically causing a rotative movement of same when so actuated.

45 8. A chambered body having a port and a flat valve seat surrounding the port, a valve member adapted to lie loosely by force of gravity upon its seat, and means for moving the valve member forward and backward 50 and also rotatively, including a rocking lever having a ball and socket connection therewith.

9. A chambered body having a port and a flat valve seat surrounding the port, a valve 55 member adapted to lie loosely by force of gravity upon its seat, and means for moving the valve member forward and backward and also rotatively, including a rocking lever having a ball and socket connection therewith which also forms a pivot bearing for its rotative movement.

10. A chambered body having a port and a flat valve seat surrounding the port, a valve member adapted to lie loosely by force of 65 gravity upon its seat, and means for moving

the valve member forward and backward and also rotatively, including a rocking lever having a ball and socket connection therewith, which also forms a pivot bearing for its rotative movement, said valve member having suitably arranged peripheral grooves for coöperation with the impinging fluid for causing its rotation. 70

11. A chambered body having a port and a flat valve seat surrounding the port, a valve member adapted to lie loosely by force of gravity upon its seat, and means for moving the valve member forward and backward and also rotatively, including a rocking member having a ball and socket connection therewith which also forms a pivot bearing for its rotative movement, said valve member having inclined grooves upon its periphery and the inlet port being so arranged relatively to said periphery that the impinging fluid flowing therethrough shall cause a rotative movement of the valve member. 80

12. A faucet comprising a chambered body provided with inlet and discharge ports and a flat valve seat for the discharge port, a sliding valve member therefor, mechanical means engaging the middle portion of the valve for actuating the same to open and close the discharge port, and means whereby the passage of fluid from said inlet to the discharge causes a rotative movement of said valve member. 90

13. A chambered body provided with inlet and discharge ports and a flat valve seat surrounding one of said ports, a sliding valve member, ball and socket means for operating said member to open and close the port surrounded by the seat, the inlet so directed as to cause the fluid to flow tangentially to the valve member to cause its rotative movement. 100

14. A chambered body provided with inlet and discharge ports and a flat valve seat surrounding one of said ports, a sliding valve member, ball and socket means for operating said member to open and close the port surrounded by the seat, the inlet so directed as to cause the fluid to flow in an upwardly inclined direction and substantially at a tangent to the valve periphery to cause 110 a rotative movement of the valve.

15. A chambered body provided with a discharge port and a flat valve seat surrounding said port, a sliding valve member having peripheral grooves, means for operating said member to open and close the port, the inlet so directed as to cause the fluid to flow tangentially to the valve member. 120

16. A chambered body provided with a discharge port and a flat valve seat surrounding the port, a sliding valve member, having inclined peripheral grooves, means for operating said member to open and close the port, the inlet so directed as to cause the 130

fluid to flow in an upwardly inclined direction and substantially at a tangent to the valve periphery.

17. A chambered body provided with inlet and discharge ports, and a flat valve seat surrounding one of said ports, a sliding valve member having peripheral grooves and adapted to lie by gravity upon said seat, a lever having a loose ball and socket con-

nexion with the center of the valve member 10 as means for operating same to open and close the port surrounded by the seat, the ports arranged to cause a flow tangentially to said member to cause it to rotate on its ball and socket connection when the valve 15 is in open position.

FREDERICK B. HIBBARD.
